(57) **CLAIM**

The ornamental design for a beverage dispenser simulating a snow globe, as shown and described.

DESCRIPTION

FIG. 1 is a top and front perspective view of a beverage dispenser simulating a snow globe showing a first embodiment of my new design;

FIG. 2 is a front elevation view thereof, the rear and sides adjacent being identical in appearance to that shown;

FIG. 3 is a top plan view thereof;

FIG. 4 is a bottom plan view thereof;

FIG. 5 is a top and front perspective view of a beverage dispenser simulating a snow globe showing a second embodiment of my new design;

FIG. 6 is a front elevation view thereof, the rear and sides adjacent being identical in appearance to that shown;

FIG. 7 is a top plan view thereof;

FIG. 8 is a bottom plan view thereof;

FIG. 9 is a top and front perspective view of a beverage dispenser simulating a snow globe showing a third embodiment of my new design;

FIG. 10 is a front elevation view thereof, the rear and sides adjacent being identical in appearance to that shown;

FIG. 11 is a top plan view thereof; and,

FIG. 12 is a bottom plan view thereof.

The broken-line disclosure of interior ornamentation, dispenser cap, and support base are understood to comprise portions of the article in which the claimed design is embodied, but which form no part of the claimed design.
